UNITED STATES PATENT OFFICE.

THOMAS W. VARLEY, OF NEW YORK, N. Y., ASSIGNEE TO WESTINGHOUSE ELECTRIC
AND MANUFACTURING COMPANY, A CORPORATION OF PENNSYLVANIA.

ELECTRICAL MEASURING INSTRUMENT.

1,140,925.

Specification of Letters Patent. Patented May 25, 1915.

Application filed April 8, 1909. Serial No. 428,653.

To all whom it may concern:

Be it known that I, THOMAS W. VARLEY, a citizen of the United States, residing in the borough of Manhattan, city, county, and State of New York, have invented a new and useful Improvement in Electrical Measuring Instruments, of which the following is a specification.

My invention relates to electrical measuring instruments of that class wherein advantage is taken of a magnet causing a substantially constant magnetic field, in combination with stationary and movable conductors so disposed that a current passing through the stationary conductor will shift or distort the lines of force of the magnet, preferably without altering the total of such lines, in such manner that they will cause a torque on the movable conductor, the function of the stationary conductor being simply to shift the lines of force of the magnet, and not necessarily to create the magnetic field itself, as in the ordinary electric dynamometer.

In the following I have described, with reference to the accompanying drawings, a structure illustrating one embodiment of my invention, the features thereof being more particularly pointed out hereinafter in the claims.

In the drawings, Figure 1 is a vertical sectional view of a structure designed to be used as a watt-hour meter. Fig. 2 is a cross sectional view of the structure shown in Fig. 1 along the line A—B, illustrating the electrical connections thereto in diagrammatic form. Fig. 3 is a perspective view of one form of movable conductor.

Similar numerals of reference indicate similar parts throughout the several views.

1 represents a substantially constant magnet, here shown in the form of a permanent magnet, having poles 2 and 3 carrying pole pieces 4 and 5 respectively. Each of said pole pieces 4 and 5 is slotted as at 6 and 7 to form polar projections 8 and 9, and 10 and 11 respectively.

12 represents a container made of any suitable insulating material, such as molded vulcanized rubber, adapted to fit within polar projections 8, 9, 10 and 11 and to be supported in such position in any suitable manner, as on bracket 13 supported from poles 2 and 3.

14 is a central upright tube, preferably

made of the same material as container 12 and forming the inner wall of the same.

15 represents a core, preferably of soft iron, provided with a covering 16 to electrically insulate the core from carrying current as hereinafter described. Core 15 may be supported on tube 14 in any suitable manner, as by threading it on the same as shown.

17 represents a cup, preferably of copper, supported from shaft 18 and depending into container 12. Shaft 18 finds a bearing at 19 on bracket 13 and at 20 in bracket 21 suitably supported on poles 2 and 3. The upper end of shaft 18 is provided with a gear wheel 22 engaging gear wheel 23 on shaft 24 adapted to drive indicator 25. Cup 17 is preferably slotted to form segments 26, as shown, said slots being preferably filled with an insulating material 27, such as rubber, to form a smooth periphery.

28 represents a second cup depending from cup 17 and made preferably of a non-magnetic material such as aluminum. Cup 28 is provided with a covering 29 adapted to insulate the cup against electric currents preferably at all points.

30 represents a conducting fluid, such as mercury, adapted to fill container 12, preferably to a point above the height of the core 15.

31, 32, 33 and 34 are conducting points passing through the walls of container 12 preferably at a point below the pole pieces and preferably located equidistant from each other and 45 degrees from a line drawn through the centers of slots 6 and 7.

35 represents a suitable source of current, shown here as a direct current generator and 36 and 37 the mains:

38 and 39 are taps taken off the mains, 38 leading to the fixed conductor, here shown as windings or coils 40, 41, 42 and 43 on polar projections 10, 11, 9 and 8 respectively, and thence through resistance 44 to tap 39 and main 37.

Main 36 as illustrated, passes through resistance 45 to one side of load 46. Main 37 leads to the other side of load 46. On either side of resistance 45 are taps 47 and 48, tap 47 divides as at 49 and leads to conducting points 31 and 33 and tap 48 divides as at 50 and leads to conducting points 32 and 34.

The function of the fixed coils is to distort or shift the lines of force of magnet 1, the amount of such distortion varying as

the voltage of the load, resistance 44 acting as a resistance to fix the amount of shift for a given voltage.

- 5 The function of resistance 45 is to act as a load shunt and gives a drop of E. M. F. across its terminals varying as the current to the load. This drop causes current to flow through taps 47 and 48 and conducting points 31 and 33 and 32 and 34 respectively into 10 the mercury 30, through the mercury to the cup 17 where it passes up segments 26 at diametrically opposite points across the top of the cup and down other segments 26 diametrically opposite each other and mid- 15 way the circumference of the first two segments. Resistance 45 may of course be omitted in which case all the load current will pass through the conducting points as stated.
- 20 The function of cup 28 is to act as a retarding element, the amount of the retarding force varying as the speed of rotation as it rotates in the constant field and induced currents are set up in it. Cup 17 be- 25 cause of the method of use with diametri- cally opposite points connected together, can act as a retarding element and cup 28 be omitted.

It is obvious that all of the current passing through the conducting points will not pass up the segments opposite the point but a portion of the current will divide and some of it pass up other adjacent segments and some of it pass around through the mer- 35 cury and out of the nearest conducting points, but such operation will not interfere with the function of the instrument as a watt-hour meter as the resistance of mer- cury is greater than that of copper.

40 The amount of torque exerted on the moving conductor will vary as the current flowing in it and the amount of shift in the constant field, these two effects varying first as the current to the load and second as the 45 potential of the load, that is, the product is the watts of the load. The combination of this torque with the retarding torque forming a watt-hour meter.

The insulation on cup 28 and core 15 pre- 50 vents current from flowing through them which would result in a partial short circuiting of the conducting points.

The principle of the invention as shown 55 and described is applicable to either alter- nating or direct currents and may be uti- lized in the construction of voltmeters and ammeters, as well as in either integrating or indicating wattmeters, as is clear to anyone skilled in the art.

60 It is obvious that the details illustrated may be considerably varied and parts and functions transposed without departing from the spirit of my invention, as, for instance, varying the number of poles or polar 65 projections or the number of windings of

the stationary conductor or the number of segments of the movable conductor, or transposing the functions of the stationary and movable conductors.

I do not restrict myself to any of the de- 70 tails as shown and described.

Having described my invention, what I claim and desire to secure by Letters Patent is:

1. A measuring instrument for an electric 75 circuit comprising a permanent magnet, a stationary winding surrounding parts of the said magnet and connected in shunt relation to the said circuit for shifting the lines of force in the said magnet, a rotatable 80 member adapted to respond to the shifting of the lines of force, a chamber within which the said rotatable member is located, a plurality of contact terminals mounted in the peripheral wall of the said chamber, and a 85 liquid conductor in the said chamber between the said contact terminals and the rotatable member.

2. A measuring instrument for an electric 90 circuit comprising a permanent magnet, a stationary winding surrounding parts of the said magnet and connected in shunt relation to the said circuit for shifting the lines of force in the said magnet, a rotatable member adapted to respond to the shifting 95 of the lines of force, a retarding element adapted to move with the said rotatable member, a chamber in which the said rotatable member is located, a plurality of uniformly spaced contact terminals mounted 100 in the peripheral wall of the said chamber, and a liquid conductor in the said chamber between the said contact terminals and the rotatable member.

3. An electrical measuring instrument 105 comprising a substantially constant magnet, a stationary conductor adapted to shift the lines of force set up by said magnet, a movable conductor adapted to respond to the shifting of said lines of force, a chamber 110 within which said movable conductor is adapted to rotate, contact terminals in the wall of said chamber, a liquid conductor in said chamber between said contact terminals and the movable conductor and a retarding 115 element moving with said movable conductor but insulated from said liquid conductor.

4. In an apparatus of the character de- 120 scribed, a movable conductor comprising an inverted cup of conducting material having a solid upper end and a peripheral wall comprising a set of uniformly spaced fingers and a set of insulating strips fitted between said fingers.

5. In an apparatus of the character de- 125 scribed, a movable conductor comprising an inverted cup of conducting material having a peripheral wall composed of a set of spaced fingers and insulating material interposed between said fingers, oppositely dis- 130

posed contact terminals adjacent to said movable conductor and an electrical conductor between said contact terminals and said movable conductor.

5 6. In an apparatus of the character described, a movable conductor comprising an inverted cup of conducting material having a solid upper end and a peripheral wall comprising a set of integral fingers and interposed insulating strips of approximately the same width as the fingers.

7. An electrical measuring instrument comprising a substantially constant magnet, a stationary conductor adapted to shift the 15 lines of force set up by said magnet, a movable conductor comprising a cup of conducting material having its side walls divided into segments and adapted to respond to the shifting of said lines of force, a mercury chamber within which said movable conductor is adapted to rotate, mercury in 20 said chamber and contact terminals in the wall of said chamber, the mercury forming

a conductor between said contact terminals and said movable conductor.

8. A measuring instrument for an electric circuit comprising a permanent magnet, a stationary winding thereon connected in shunt relation to the said circuit for shifting the lines of force in the said magnet, a movable conductor comprising an inverted cup of conducting material having a solid upper end and a peripheral wall comprising a set of integral fingers and interposed insulating strips, and means for providing the said 85 movable conductor with current proportional to the current traversing the said circuit.

In testimony whereof I have signed this specification in the presence of two subscribers 40 and witnesses.

THOMAS W. VARLEY.
